UNITED STATES PATENT OFFICE.

FREDERICK A. LINTON, OF NEW BRITAIN, CONNECTICUT.

BANJO.

SPECIFICATION forming part of Letters Patent No. 787,777, dated April 18, 1905.

Application filed April 19, 1904. Serial No. 203,946.

To all whom it may concern:

Be it known that I, FREDERICK A. LINTON, a citizen of the United States, residing at New Britain, in the county of Hartford and State 5 of Connecticut, have invented certain new and useful Improvements in Banjos, of which the following is a specification.

My invention relates to improvements in banjos; and the main objects of my improvements are simplicity and economy in construction and convenience and efficiency in use.

In the accompanying drawings, Figure 1 is a plan view of the main portion of my banjo, the neck being represented as broken off. Fig. 2 is a side elevation of the same. Fig. 3 is a reverse plan view. Fig. 4 is a sectional view of a portion of the same on the line α of Fig. 1. Fig. 5 is a sectional view of a portion of the same on the line γ of Fig. 1.

20 A designates the rim or the main portion of the head, which rim I make of a bell shape or flaring form instead of the usual cylindrical form. The usual brace or cross-piece B extends across the said rim on the inside as

25 a continuation of the neck C. The rim 4 is preferably made of a wooden body with a metal covering 6. The usual parchment 7, which covers the head, is mounted on the usual hoop 8 and stretched by means of the 30 usual ring 9 and clamping-screws 10. Instead of the usual brackets on the outside of the rim these screws are passed through the rim itself, the bell-shaped form enabling it to be done, the ends of the screws projecting on the 35 inner side of the rim. I prefer to place a washer 11 over each screw and on the said washer place the nuts 12. The essential thing, however, is the nuts or equivalent threaded

holes for the rotating screws, arranged with their threaded ends inside of the outer surface 40 of the rim. The ring is provided with suitable holes, through which the screws 10 pass, and is drawn down to bear on the parchment-covered hoop and stretch the said parchment by turning the screws 10, while the nuts 12 45 are stationary. The neck may be of any ordinary construction, as also may be the tail-piece 13 for securing the end of the strings 14.

I am aware that banjo-frames have been constructed with an annular portion for concealing the threaded ends of the clamping-screws and the nuts, and hence I do not broadly claim such as my invention.

By my improvement the construction is simple and inexpensive, while by passing the 55 screws through the rim into nuts or threaded holes on the inside of the said rim the outermost projecting face of the said rim is left smooth and free from all objectionable projections. It is also believed that the bell-shaped rim gives the instrument a better tone and an increased volume of sound.

I claim as my invention—

In a banjo, the combination of the rim having a flaring bell-shaped body with the parchment, hoop, ring, and rotating clamping-screws, the said clamping-screws passing through holes in the said ring and through the slanting sides of the flaring bell-shaped portion of the said rim, and screwed into 70 threaded holes inside of the outer slanting surface of the said bell-shaped rim.

FREDERICK A. LINTON.
